UNITED STATES PATENT OFFICE.

LESLIE O. CONNER AND GEORGE R. HALE, OF NARROWS, VIRGINIA.

ARTIFICIAL LEG.

1,104,413.

Specification of Letters Patent. Patented July 21, 1914.

Application filed November 20, 1913. Serial No. 802,136.

To all whom it may concern:

Be it known that we, LESLIE O. CONNER and GEORGE R. HALE, citizens of the United States, residing at Narrows, in the county of Giles, State of Virginia, have invented a new and useful Artificial Leg, of which the following is a specification.

The object of the invention is to improve the knee joint connection between the thigh 10 and the calf of an artificial leg.

In the drawing:—Figure 1 shows the invention in side elevation; Fig. 2 is a vertical longitudinal section; Fig. 3 is a rear elevation of the knee spring, attendant parts 15 being shown in elevation; and Fig. 4 is a fragmental front elevation of the calf.

The artificial leg herein disclosed comprises a tubular thigh 1 and a tubular calf 2. The lower end of the thigh 1 extends into 20 the upper end of the calf 2. Bearings 3 are secured to the sides of the calf 2 and receive a pivot element 4 which, passing through the lower end of the thigh 1, affords a hinged joint between the thigh and the calf.

25 The invention further includes a knee spring which, generally considered, is of U-shape, the knee spring being shown in clearest outline in Fig. 3. The upper, curved end 5 of the knee spring bears against a stop pin 6 which extends across the interior 30 of the thigh 1. The side portions 7 of the spring are bent upon themselves to form eyes 8 which surround the pivot element 4. One eye 8 of the spring is prolonged to form a 35 depending arm 9 having a lateral extension 10, the same terminating in a forwardly presented, angularly disposed finger 11 which is shown in Fig. 2. The other eye 8 of the spring is prolonged to form an arm 12 terminating in a rectangularly disposed extension 14 having a depending terminal finger 15.

Located within the tubular calf 2 is a primary brace 16, the lower end of which bears 45 against the front portion of the calf 2, as shown at 17. Any suitable means may be provided for holding the brace 16 in place on the calf 2. In the present instance, spaced 50 openings 18 are formed in the front wall of the calf 2, as shown in Fig. 5, and through these openings 18 is extended a thong 19 which passes around the lower end 17 of the brace 16. The exposed ends of the thong 19 are crossed upon the outer face of the calf 2 55 as will be understood from Fig. 4, and

through the exposed ends of the thong at their point of crossing 20, is inserted a nail 21 or like securing element. The extension 10 of the arm 9 bears against the rear edge of the primary brace 16, adjacent the upper 60 end of the brace, and the finger 11 extends along the side face of the brace 16, as shown in Fig. 2, and is secured to the brace.

The invention further includes a secondary brace 22, located within the tubular calf 2. 65 By means of securing elements 23, the secondary brace 22 is held in place at its lower end in the calf 2. At its upper end, the secondary brace 22 is equipped with a transverse slot 24. The transverse extension 14 of the 70 arm 12 of the spring rests in the slot 24 and the finger 15 extends along one side face of the brace 22, as will be understood from Fig. 4. A resilient buffer 25, made of rubber or the like, is secured to the thigh 1 adjacent the 75 lower end thereof, the buffer 25 lying in the path of the upper end of the primary brace 16. The braces 16 and 22, although resilient, so as to swing vertically in a direction 80 parallel to the plane of swinging movement of the calf 2, are held against longitudinal movement.

Since the braces 16 and 22 are resilient the braces together with the knee spring shown in Fig. 3 may be described generally 85 as a "resilient structure".

When the calf 2 is swung rearwardly, or when the knee portion of the device is moved forwardly, the U-shaped spring will be put under tension because the end 5 of the spring 90 bears against the pin 6 and because the arms 9 and 12 of the spring are operatively connected, respectively, with the primary brace 16 and with the secondary brace 22. The function of the U-shaped spring is to swing 95 the calf 2 forwardly, and this swinging motion is enhanced by the braces 16 and 22 which are resilient. The brace 16 serves to prevent the knee from knuckling backwardly, and it is to be observed that by 100 loosening the thong 19, the brace 16 may be adjusted vertically.

Having thus described the invention, what is claimed is:—

1. In an artificial leg, a thigh; a calf; a 105 pivot element connecting the thigh with the calf; a spring comprising arms, the spring being engaged in its intermediate portion with the pivot element; means upon the thigh for engaging one end of the spring; 110

braces connected with the arms of the spring and located within the calf; and means for connecting the braces with the calf.

2. In an artificial leg, a thigh; a calf; a pivot element connecting the thigh with the calf; a spring bearing in its intermediate portion upon the pivot element and comprising arms; means upon the thigh for engaging one end of the spring; forward and rear braces located within the calf and connected with the arms of the spring; means for securing the rear brace to the calf; the forward brace being longitudinally adjustable upon the calf; and the calf engaging means operating with the forward brace to hold the same fixed in adjusted positions.

3. In an artificial leg, a thigh; a calf pivotally connected therewith; forward and rear braces attached adjacent their lower ends to the calf; upwardly extending resilient elements connected at their lower ends with the braces; means upon the thigh for receiving the upper portions of the resilient elements; and means upon the thigh for supporting the resilient elements intermediate their ends.

4. In an artificial leg, a thigh; a calf; forward and rear braces secured to the calf; springs connected with the braces adjacent

their upper ends; and means for connecting the springs with the thigh.

5. In an artificial leg, a thigh; a calf pivotally connected therewith; a brace connected with the forward portion of the calf; a spring connected with the upper end of the brace; means upon the thigh for engaging the upper portion of the spring.

6. In an artificial leg, a thigh; a calf pivotally connected therewith; a brace located within the calf and secured adjacent its lower end to the rear portion of the calf; a spring connected with the upper end of the brace; and means upon the thigh for engaging the spring.

7. In an artificial leg, a thigh; a calf pivoted thereto; and a resilient structure secured to the thigh; the resilient structure comprising downwardly extended portions secured, respectively, adjacent their lower ends to the front and rear walls of the calf.

In testimony that we claim the foregoing as our own, we have hereto affixed our signatures in the presence of two witnesses.

LESLIE O. CONNER.
GEORGE R. HALE.
